UNITED STATES PATENT OFFICE.

GEORGE E. RANDLES, OF CLEVELAND, OHIO, ASSIGNOR TO THE FOOTE-BURT COMPANY, A CORPORATION OF OHIO.

WASHING MACHINE.

Application filed May 27, 1924. Serial No. 716,254.

To all whom it may concern:

Be it known that I, GEORGE E. RANDLES, a citizen of the United States, residing at Cleveland, county of Cuyahoga and State of 5 Ohio, have invented certain new and useful Improvements in Washing Machines, of which the following is a specification.

The present invention relates to motor-operated washing machines, and especially to 10 washing machines of the suction cup or pounder type wherein the washing is performed by suction cups or bells which are carried by a reciprocating plunger rod and are brought down into engagement with the 15 material being washed, and wherein there is provided a clutch for connecting the motor to and disconnecting it from the operating means for the plunging rod.

In connection with such machines it is desirable 20 when clothing is in the tub being washed, that when the clutch is thrown from "in" to "out" position to stop the washing machine, that the plunger rod should stop at the top of its stroke and be held in such 25 position, so that the suction cups or bells will be above the material being washed, and one object of my invention is to provide an improved construction for accomplishing this result. By my improved construction and 30 arrangement the clutch when operated will move from "in" to "out" position only when the plunger rod is at the top of its stroke and the suction cups are above the material in the tub being washed. Also when it 35 moves to "out" position it effects the holding or locking of the plunger rod in such position.

But little force is required in normal operation to move the clutch from one position 40 to the other so that, so far as moving the clutch is concerned, the operating means for it may be light in weight and simple in structure. However, it happens sometimes that with too much material in the tub the 45 washing machine stalls and when this happens the clutch will be held "in" tightly. Under these circumstances to move the clutch to "out" position requires considerable force, and, if it is not amply strong, the operating mechanism for the clutch 50 may be bent or otherwise damaged by the operator when trying to throw the clutch. Of course, the thing the operator should do 55 is to remove the material which is stalling the machine but even though instructed to

do so, often an operator will not do it but rather will try to throw out the clutch. For this reason clutch-operating mechanisms have been made usually quite heavy but even then they have been damaged 60 sometimes by the operator in trying to throw out the clutch when the machine was stalled. A further object accomplished by my invention is that the arrangement is such that the amount of force which can be 65 exerted by the clutch-operating mechanism on the clutch is definitely limited so that in no case can the operator injure the clutch-operating mechanism in trying to throw the clutch out. This enables me to use a clutch-operating mechanism which is light in 70 structure without danger of its being injured.

A still further object of my invention is to provide an improved arrangement of 75 clutch and driving shafts which is simple in structure and easy to assemble, and which provides good bearing surfaces for the various parts.

For a consideration of what I believe to 80 be novel and my invention, attention is directed to the accompanying description and the claims appended thereto.

In the drawing, Fig. 1 is a side elevation, with certain parts broken away, of a washing machine embodying my invention; Fig. 2 is a detail sectional view through the clutch and driving mechanism; Fig. 3 is a detail perspective view of the clutch; Fig. 4 is a vertical, sectional view showing the parts 85 in one position; Fig. 5 is a view similar to Fig. 4 showing the parts in another position; Fig. 6 is an end view of the operating mechanism, and Fig. 7 is a detail sectional view taken on line 7—7, Fig. 4. 90

Referring to the drawing, 1 indicates the tub of the washing machine, 2 the frame in which it is mounted, 3 the legs, and 4 the casing or housing which contains the operating mechanism of the machine. In the 100 tub are the suction cups or bells 5 carried by a suitable yoke 6 which in turn is attached to the plunger rod 7. Plunger rod 7 projects down through a tubular post 8 into casing or housing 4, a suitable packing 105 (not shown) being provided at the point where it passes through the top of the casing to prevent leakage into the casing. The lower end of plunger rod 7 is tubular as shown particularly in Figs. 6 and 7 and 110

it slides on a guide post 9 which is supported at its lower end in a socket 10 formed in a boss 11 on a wall of casing 4, the post being free to turn on its vertical axis in such socket. Suitably attached to the lower end of plunger rod 7 is a spool or head 12 provided with a groove 13 with which engage forks 14 on the end of an arm 15. Arm 15 is attached to and forms a part 10 of a cross head 16 which slides on a vertical guide post 17 supported at its two ends in the top and bottom walls of casing 4. Cross head 16 is provided with two fingers 18 (Fig. 7) which engage opposite sides of 15 a rectangular bar 19 supported in the top and bottom walls of the casing. This serves to hold the cross head from turning on post 17 while permitting it to slide thereon. Spool or head 12 is provided with opposed 20 keys 20 which slide in vertical keyways 21 in guide post 9. With this arrangement when cross head 16 is reciprocated on guide post 17 it moves the plunger rod 7 up and down, the keys 20 sliding in keyways 21, to 25 reciprocate the suction cups, and when guide post 9 is turned on its vertical axis in socket 10 it turns also the plunger rod 7 to give a turning movement to suction cups 5, since it is connected to it by the keys 20 and keyways 21. When plunger rod 7 turns, spool or head 12 turns in the forks 30 14.

On the lower end of cross head 16 is a crank pin 22 connected by a link 23 to a 35 crank pin 24 on the end of a crank arm 25. (See Fig. 2.) Crank arm 25 is carried by and in the present instance is shown as being formed integral with a hollow shaft 26 journaled in a suitable bearing 27. Extending 40 through shaft 26 and journaled therein is a driving shaft 28 having a head 29 on its end which rests against the forward end of shaft 26. Beyond bearing 27 is a second bearing 30 suitably supported from a 45 wall of casing 4 and in which the other end of driving shaft 28 is journaled. Fastened on the end of driving shaft 28 is a bevel gear wheel 31 which is fixed in position by a pin 32. The hub of bevel gear 50 wheel 31 engages the end of bearing 30 so that when pin 32 is in position it serves not only to attach the bevel gear wheel to shaft 28 but also to hold shaft 8 in position in its bearings and prevent it from moving 55 axially.

Bevel gear wheel 31 is the wheel which drives the vertical wringer shaft for effecting operation of the wringer. This shaft is not shown in the drawing but the arrangement of such shafts is well understood in this art. The arrangement may be for example, that shown in my Patent No. 1,520,886, Dec. 30, 1924, or that shown in my Patent No. 1,520,887, Dec. 30, 1924.

65 On shaft 28 adjacent to bearing 30 is a

worm wheel 33 which is fixed to the shaft by a pin 34. Meshing with worm wheel 33 is a worm 35 carried by a shaft 36. Shaft 36 is journaled in suitable bearings in casing 4 and is driven by a suitable motor (not 70 shown). Mounted on shaft or sleeve 26 is a clutch comprising a clutch collar 37 and a clutch pin 38 adapted to enter an opening 39 in the web of worm wheel 33. Clutch collar 37 is fastened to shaft 26 by a key 75 40 so that it turns with the shaft but can be moved axially on the shaft to bring pin 38 out of and into an opening 39. In the present instance two openings 39 are shown with either of which the pin may engage. 80

With the above-described arrangement it will be seen that when the motor is running, worm 35 drives worm wheel 33 and the shaft 28 on which the worm wheel is mounted. If now the clutch is in "in" position as shown in Figs. 2 and 4, the clutch pin 38 being in one of the openings 39, then the shaft or sleeve 26 will be connected to worm wheel 33 and will turn with it. This will turn crank 25 and through link 23 90 the cross head 16 will be moved up and down thus imparting reciprocating movement to plunger rod 7 and the suction cups or bells carried by it. On the other hand, when the clutch is thrown to "out" position, as indicated in Fig. 5, the clutch pin 38 being removed from openings 39, then shaft or sleeve 26 will remain stationary, shaft 28 turning in the shaft or sleeve 26. 95

Now, according to one feature of my invention, I provide a spring means for throwing the clutch from "in" to "out" position and an operating means for storing up energy in the spring means, and I then arrange the spring means and the operating means therefor so that the energy stored in the spring means will be sufficient for throwing the clutch out only when the suction cups are above the material in the tub being washed and the crank is passing over dead center at the upper end of the stroke of the plunger rod. In this connection it is pointed out that when the worm wheel is transmitting motion through the clutch to shaft 26 to reciprocate the plunger rod, the clutch pin 38 is pressed against the sides of the opening 39 in which it is located with some force, particularly when the bells or suction cups are passing through the water and clothes in the tub, so that 105 friction tends to hold the pin against movement out of the opening. However, when the bells or suction cups are above the water and clothes in the tub and crank arm 25 is passing over dead center at the top of the stroke, the pressure on the clutch pin is relieved temporarily during the time the force acting on the connecting rod changes from a tension force to a compression force 110 and at this time the pin can be moved easily 115

120

125

130

- from the opening. I therefore provide a clutch operating means which when actuated to throw the clutch to "out" position, stores up only enough energy in the spring 5 to throw the clutch to "out" position when there is little load being transmitted, which condition occurs, when washing is being done, at the time when the crank is passing over dead center at the top of its stroke.
- 10 With this arrangement, therefore, no matter during what portion of the stroke the clutch-operating means is actuated, the clutch will not release until the bells or suction cups are at the top of their stroke. In
- 15 connection with this arrangement, I provide also means whereby when the clutch throws out it serves to hold the bells or suction cups in such top position.

Referring now specifically to the drawing, clutch collar 37 is provided with an annular groove 41 in which is located a head 42 on the end of a lever arm 43. Lever arm 43 is fastened on the lower end of a shaft 44 which is pivoted in a wall of casing 4 as shown in Figs. 1 and 6, the lower end of shaft 44 being inside the casing and the upper end outside the casing. In this connection it will be noted that the casing has been omitted in Figs. 3, 4 and 5 so as to 20 illustrate the construction more clearly. Attached to the upper end of shaft 44 is a lever arm 45 which is located outside casing 4. In the end of lever arm 45 is an opening 46 through which projects freely one end 25 of a connecting rod 47. The other end of connecting rod 47 is attached to a crank 48 on the lower end of an operating rod 49. Operating rod 49 is suitably journaled at its two ends in the frame of the washing machine as is indicated at 50 and at its upper 30 end is provided with an operating handle 51. On the lower end of crank 48 beneath the eye in connecting rod 47 through which the end of the crank projects is a washer 51^a which when the crank is turned from one position to the other strikes the inner surface of the lower frame ring 51^b to limit the throw of the crank. In other words, washer 51^a cooperating with frame ring 51^b 35 serves as a stop for limiting the throw of the crank. On connecting rod 47 is a washer 52 held by a cotter pin 53 and located between washer 52 and the end of lever arm 45 is a spring 54 which surrounds 40 the rod. On the end of rod 47 is a washer 55 held by a cotter pin 56 which washer engages lever arm 45 on the side opposite to that which spring 54 engages.

In Fig. 1 the handle 51 is shown as being 45 in its extreme left hand position at which time the clutch is in "in" position. The clutch is held in this position by a spring pressed ball 57 which engages a depression 58 in shaft 26. If now the machine is 55 running and it is desired to throw out the

clutch, handle 51 is moved toward the right as seen in Fig. 1. This turns crank 48 toward the left and moves connecting rod 47 toward the left pushing spring 54 against the end of lever arm 45. Lever arm 45 70 offers resistance to movement because of the pressure of clutch pin 38 in opening 39 and as a result the end of connecting rod 47 will be pushed through opening 46, spring 54 being put under compression. 75 This is shown in Fig. 4 where the operating handle is shown as having moved connecting rod 47 to put spring 54 under compression to throw out the clutch. The clutch, however, is still in. Now, when the crank 80 arm passes over dead center at the top of its stroke, the pressure of pin 38 in opening 39 will be relieved as already explained, whereupon spring 54 will expand and quickly snap the clutch to "out" position. 85 This is shown in Fig. 5 where it will be seen that the clutch has moved to "out" position. Spring 54 is made of such strength and the throw of crank 48 of such length that the turning of handle 51 from its one extreme position to the other stores only sufficient force in spring 54 as to throw the clutch "out" when there is little if any load on the mechanism, which when washing is being done means when the suction cups are 90 above the materials in the tub.

Clutch collar 37 is provided with a surface 59 which when the clutch moves to "out" position engages a surface 60 at one side of bearing 27 and it is held tightly 100 against this surface by spring 54 which is arranged so that it is still under compression to some extent when the clutch is "out." This serves as a friction brake or lock to hold the crank arm (and hence the suction 105 cups or bells) at the top of their stroke. At this time spring pressed ball 57 engages a depression 61 in shaft 26 and assists somewhat in holding the clutch in braking position.

To throw the clutch in again, handle 51 is turned back to the left hand position whereupon the cotter pin 56 which engages the end of lever arm 45, serves to effect a positive movement of lever arm 45, shaft 44 115 and lever arm 43 to move the clutch to bring clutch pin 38 back into one of the openings 39. As seen in Fig. 3, there are curved recesses 62 leading to openings 39 to guide the pins into them.

As pointed out above, the throw of handle 51 is limited by the washer 51^a. If the machine is stalled with the clutch in, throwing the operating handle from "in" to "out" position will serve only to put spring 54 125 under compression. No additional force can be put on the clutch operating mechanism so that under these circumstances the material stalling the machine must be removed before the clutch will open to en- 130

able the machine again to be put into operation.

Formed integral with crank arm 25 and shaft 26 is a gear wheel 63 which meshes with a gear wheel 64 pivoted on a stud 65 (Fig. 2) attached to a wall of housing 4. Projecting from the face of gear wheel 64 is an actuating pin 66 and a locking segment 67. These cooperate with actuating slots 68 and locking slots 69 formed in the periphery of a disk 70. Disk 70 forms what may be termed a star wheel. Disk 70 is fastened on a transverse shaft 71 journaled in suitable bearings 72 and 73 in the housing walls. On shaft 71 is a spiral gear wheel 74 which meshes with a spiral gear wheel 75 fixed on the lower end of guide post 9. This mechanism serves to give a step by step turning movement to the suction cups and operates as follows:—

Gear wheel 63 turns with crank arm 25 and each time the crank arm and gear wheel make one revolution, gear wheel 63 turns gear wheel 64 one revolution the two gear wheels being the same size. During the major portion of the revolution of gear wheel 64, locking segment 67 lies in one of the locking slots 69 of star wheel 70, locking it against turning movement. As locking segment 67 leaves a slot 69, actuating pin 66 engages the adjacent actuating slot 68 and turns star wheel 70 through a definite angle. When pin 66 leaves the slot 68, segment 67 engages the next locking slot 69 and again locks the star wheel 70 against movement. When star wheel 70 turns, it turns shaft 71 through the same angle and this through spiral gears 74 and 75 turns guide post 9, plunger rod 7 and suction cups 5 through a corresponding angle. The arrangement is such that the suction cups are given this turning movement at the top of the stroke while they are above the materials in the tub which are being washed. During the remaining portion of the stroke they are locked against turning movement by locking segment 67. This construction and arrangement for giving a step by step turning movement is described only generally herein as it forms no part of the present invention. It is more fully disclosed and is claimed in my aforementioned Patent No. 1,520,886.

At 76 is indicated a counter weight for crank arm 23 and at 77 is indicated an oil scraper which forms a part of the lubricating system for the machine. The lubricating system forms the subject matter of my application Sr. No. 716,252 filed of even date herewith.

In connection with the arrangement of shafts 26 and 28 and the parts carried thereby, it will be seen that they can be very quickly and easily assembled. Shaft 26

and the key 40 and clutch 37 then mounted thereon. After this shaft 28 can be slipped axially through shaft 26, worm wheel 33 and its bearing 30. Bevel gear wheel 31 may be then fastened in place, pin 32 serving to hold the parts assembled. Pin 34 may be then put into position to fasten worm wheel 33 to shaft 28. To dismantle the mechanism it is only necessary to remove pins 32 and 34 and then pull the shafts 26 and 28 axially from their bearings.

In accordance with the provisions of the patent statutes, I have described the principle of operation of my invention, together with the apparatus which I now consider to represent the best embodiment thereof, but I desire to have it understood that the apparatus shown is only illustrative and that the invention may be carried out by other means.

What I claim as new and desire to secure by Letters Patent of the United States, is:—

1. In a washing machine, the combination of a reciprocating washing device, a driving shaft, a clutch for connecting the shaft to and disconnecting it from said device, and operating means for the clutch, said operating means including a spring member through which the operating means moves the clutch.

2. In a washing machine, the combination of a washing device which moves into and out of engagement with the materials being washed, a driving shaft, a clutch for connecting the shaft to and disconnecting it from said washing device, and operating means for moving the clutch, said operating means including a spring through which the operating means moves the clutch to out position, said spring being sufficiently strong to move the clutch to "out" position only when the washing device is not in contact with the materials being washed.

3. In a washing machine, the combination of a reciprocating washing device which moves into and out of engagement with the materials being washed, a driving shaft, a clutch for connecting the shaft to and disconnecting it from said device, operating means for moving the clutch, and means whereby when the clutch is thrown to out position it effects holding of the washing device against movement.

4. In a washing machine, the combination of a reciprocating washing device which moves into and out of engagement with the materials being washed, a driving shaft, a clutch for connecting the shaft to and disconnecting it from said device, operating means for moving the clutch, said operating means including a spring in which power is stored for moving the clutch to out position, and means of which the clutch forms a part for holding the washing device.

against movement when the clutch is thrown to out position.

5. In a washing machine, the combination of a reciprocating washing device which

5 moves into and out of engagement with the materials being washed, a driving shaft, a clutch for connecting the shaft to and disconnecting it from said device, operating means for moving the clutch, said operating 10 means including a spring in which power is stored for moving the clutch to out position, the power stored in said spring being sufficient for moving the clutch to out position only when the washing device is above 15 the materials being washed, and means which becomes effective when the clutch is thrown to out position for holding the washing device in the position it occupies at the time the clutch is thrown out.

20 6. In a washing machine, the combination of a reciprocating washing device which moves into and out of engagement with the materials being washed, a driving shaft, a clutch for connecting the shaft to and disconnecting it from said device, a lever arm for moving the clutch, a spring which engages the lever arm, and operating means for throwing the clutch to out position through the intermediary of said spring, 25 said operating means being capable of storing an amount of energy in the spring sufficient to throw the clutch to out position only when the washing device is above the material being washed.

30 7. In a washing machine, the combination of a reciprocating washing device which moves into and out of engagement with the materials being washed, a driving shaft, a clutch for connecting the shaft to and disconnecting it from said device, a lever arm for moving the clutch, a spring which engages the lever arm, operating means for storing energy in the spring for moving the clutch to out position, and 45 means for limiting the movement of said operating means.

8. In a washing machine, the combination of a reciprocating washing device, a driving shaft, a clutch for connecting the driving shaft to and disconnecting it from said washing device, means for positively moving the clutch to in position and a yielding spring through which it is moved to out position whereby the amount of 55 energy which can be applied to move the clutch to out position is limited.

60 9. In a washing machine, the combination of a reciprocating washing device, means including a rotating element for imparting reciprocating movement to said washing device, a driving shaft, a clutch for connecting the driving shaft to and disconnecting it from said rotating element, said clutch sliding on the rotating element, and a stationary member with which the clutch en-

gages when thrown to out position whereby it serves to hold the rotating element from movement and the reciprocating device in a definite position.

70 10. In a washing machine, the combination of a reciprocating washing device, a rotating element for imparting reciprocating movement to it, a driving shaft, a clutch for connecting the rotating element to and disconnecting it from said driving shaft, a lever arm for moving the clutch, said arm having an opening in its end, an actuating rod which projects through said opening, an abutment on said rod, and a spring which at one end engages said abutment and at 75 the other end engages the end of said arm.

80 11. In a washing machine, the combination of a reciprocating washing device, a rotating element for imparting reciprocating movement to it, a driving shaft, a clutch for connecting the rotating element to and disconnecting it from said driving shaft, a lever arm for moving the clutch, said arm having an opening in its end, an actuated rod which projects through said 85 opening, an abutment on said rod, a spring which at one end engages said abutment and at the other end engages the end of said arm, and means for limiting the movement of said rod whereby the energy which may be stored in said spring will be sufficient to throw the clutch out only when substantially no load is being transmitted through it.

90 12. In a washing machine, the combination of a casing, a bearing therein, a hollow shaft journaled in said bearing, a driving shaft journaled in the hollow shaft, a gear wheel on the driving shaft, and a clutch which slides on the hollow shaft to connect it to said driving shaft, said clutch when in out position engaging the end of said bearing to hold the hollow shaft against movement.

100 13. In a washing machine, the combination of a casing, a bearing therein, a hollow shaft journaled in said bearing, a driving shaft journaled in the hollow shaft, a gear wheel on the driving shaft, a clutch which slides on the hollow shaft to connect it to said driving shaft, said clutch when in out position engaging the end of said bearing to hold the hollow shaft against movement, and spring means in which energy is stored for quickly moving the clutch from in to 110 out position.

115 14. In a washing machine, the combination of a bearing, a second bearing in spaced relation to the first bearing, a hollow shaft in said first bearing, a second shaft which extends through said hollow shaft and the second bearing and is journaled therein, a head on the second shaft which engages the end of the first shaft, a gear wheel on the second shaft located between 120 125 130

the end of the hollow shaft and said second bearing, a clutch on the hollow shaft for engagement with said gear wheel, and a pin in the end of the second shaft beyond the 5 second bearing for holding the structure assembled.

15. In a washing machine, the combination of a bearing, a second bearing in spaced relation to the first bearing, a hollow shaft in the first bearing, a driving shaft which extends through the hollow shaft and the second bearing and is journaled therein, a head on the end of the driving shaft

which engages the end of the hollow shaft, a gear wheel on the driving shaft between 15 the end of a hollow shaft and the second bearing, a gear wheel fastened on the end of the driving shaft beyond the second bearing, and serving to hold the structure assembled, and a clutch on the hollow shaft which 20 moves from engagement with the gear wheel into engagement with the end of the first-named bearing.

In witness whereof, I have hereunto set my hand this 23rd day of May, 1924.

GEORGE E. RANDLES.
